UNITED STATES PATENT OFFICE.

GEORGE HEINISH, OF AKRON, OHIO, ASSIGNOR TO THE STAR DRILLING MACHINE COMPANY, OF AKRON, OHIO, A CORPORATION OF OHIO.

CARBURETOR.

Application filed August 5, 1925. Serial No. 48,279.

This invention relates to carburetors for internal combustion engines. The chief object of the invention is to provide a combined gasoline and gas carburetor of simple, inexpensive but highly effective construction, wherein the throttle and choke used for controlling the supply of gasoline and air mixture to the engine may be also employed for controlling the supply of gas and air mixture to the engine.

Another object is to provide an attachment capable of being connected to a standard gasoline carburetor to adapt the same for use either with gasoline or gas.

Another object is to provide an improved system for supplying gas to a carburetor such as is described above.

The foregoing and other objects are obtained by the construction illustrated in the accompanying drawings and described below. It is to be understood that the invention is not limited to the specific form thereof shown and described.

Of the accompanying drawings:

Figure 1 is a side elevation of an internal combustion engine provided with the carburetor of the invention and having the gas supplying system connected thereto;

Figure 2 is a side elevation of the carburetor; and

Figure 3 is a section on line 3—3 of Figure 2 through the gas-supplying attachment.

Referring to the drawings, 10 indicates generally any suitable form of internal combustion engine mounted on any suitable support such as timbers 11, 11 forming part of the framework of a machine, such as an oil well drilling or other machine, to be operated or driven by the power unit. Unit 10 has connected thereto in the usual manner, a carburetor 12 which may be of a standard type provided with an attachment whereby the objects of the invention are obtained or which may be originally constructed so as to embody the features of the invention.

As best illustrated in Figure 2, the carburetor 12 is preferably of that standard type in which the air choke valve body 13 is a separate piece arranged to be detachably connected onto the body portion 12 of the carburetor by screws (not shown) extending through mating apertured lugs indicated at 14, and 14^a respectively on the carburetor proper and the valve body 13. This form of carburetor permits of the ready insertion

of a gas valve body 15 between the carburetor proper and the air choke valve body 13, the body 15 having apertured lugs 16, 16^a therein adapted to mate with lugs 14 and 14^a so that the valve body 13 and carburetor 12 can be secured together by screws 16^a, 16^a with the gas supply valve body 15 interposed therebetween.

Supply of gasoline to carburetor 12 is effected in the usual manner from a tank (not shown) through a lead line 17 which has therein a valve 18 arranged adjacent engine 10 to cut off the supply of gasoline when gas is to be used for fuel. The usual engine throttle on the carburetor is indicated at 19 and the throttle control lever at 20.

Supply of air to the carburetor is effected by suction through an air cleanser 21 attached onto valve body 13, and is controlled by a choke valve 22 operable by a control lever 23 to which is connected the usual control wire 24.

It will appear from the foregoing that in the specific construction illustrated, the gas supply attachment 15 is arranged between the engine throttle 19 and the choke valve 22. In carrying out the invention with other forms of carburetors having an integral carburetor and air choke valve body, it may be necessary to supply the equivalent of choke valve 22 with the attachment 15.

The supply of gas to the carburetor 12 is effected through a needle valve 25 adjustable by means of a screw 26 threaded through valve body 15 and adapted to be retained in adjusted positions by means of a spring latch 27 engaging a knurled operating head 28 on screw 26. Valve 25 extends across a bore 29 through valve body 15 into one end of which is threaded a sealing plug 30, and to the other end of which is connected a gas supply line 31.

Supply line 31 is connected through a valve 32 with a supply tank or reservoir 33 mounted on frame 11 and having a low pressure gauge 33^a thereon. Supply of gas at low pressure to tank 33 is effected through a supply line 34 leading to any suitable source (not shown) of natural or artificial gas and having a low pressure regulator 35 therein.

The provision of the foregoing system for supplying gas under low pressure to the carburetor is desirable for the reason that a rapidly flowing gas cannot be properly

mixed with air in the carburetor. With gas under such pressure that it will just flow through valve 25, it is possible by proper adjustment of choke 22 to obtain the required flow of air to thoroughly mix the gas and air in the carburetor.

In use, the same throttle 19 and the same choke 22 are employed whether the fuel is gasoline or gas. If the former, valve 18 is opened, valve 32 is closed, and under normal condition, except when starting, choke 22 will be open to its fullest extent. If gas is to be used, valve 18 is closed and valve 32 is opened, and valve 25 is adjusted until the desired flow of gas is obtained, choke 22 being partly closed to increase the velocity of air to that at which the gas is supplied to obtain the proper mixture.

It will appear from the foregoing that a simple but effective combined gasoline and gas carburetor has been provided. It will also appear that a simple attachment has been devised for adapting standard gasoline carburetors for use also with natural or ar-

tificial gas, and, in addition, an improved system for supplying natural gas to a carburetor has been developed.

Modifications of the invention may be resorted to without departing from the spirit of the invention or the scope of the appended claim.

What I claim is:

In combination with a liquid fuel carburetor having a choke valve body detachably secured thereon, of a gaseous fuel supplying attachment adapted to be interposed between the body portion of said carburetor and said choke valve body, said attachment having a valve for controlling the flow of gaseous fuel to the carburetor, whereby said carburetor is adapted for supplying a proper mixture of either liquid or gaseous fuel with air to an internal combustion engine, the choke valve controlling the admission of air independently of the admission of the gaseous fuel.

GEORGE HEINISH,
